UNITED STATES PATENT OFFICE.

WILLARD C. AVERILL, JR., OF HOUSTON, TEXAS.

PROCESS OF DISTILLING HYDROCARBONS.

1,375,245.

Specification of Letters Patent. Patented Apr. 19, 1921.

Application filed July 12, 1919. Serial No. 310,334.

To all whom it may concern:

Be it known that I, WILLARD C. AVERILL, Jr., residing in Houston, in the county of Harris and State of Texas, a citizen of the 5 United States, have invented or discovered certain new and useful Improvements in Processes of Distilling Hydrocarbons, of which the following is a full, clear, and complete disclosure.

10 My invention relates to the art of distillation and has as one of its objects the provision of a method and apparatus by the use of which larger yields of high grade products may be obtained than has heretofore been customary from the same grades 15 of crude oil and also to provide a method and apparatus by means of which the fuel used in distilling a given quantity of crude liquid may be reduced to a minimum. With 20 these objects in view my invention, briefly stated, consists in passing flue gases through the heated body of oil or the like in the still and then separating the flue gases from the entrained vapors, and the apparatus 25 whereby these steps may be carried out.

The novel features of my invention are pointed out in the appended claim. The invention itself, however, together with further objects and advantages, will best be 30 understood by reference to the following description taken in connection with the accompanying drawing, in which the figure is a sectional elevation, diagrammatic in character, of the preferred form of my 35 proved apparatus for carrying out my process.

In said figure, 1 is a furnace preferably arranged to burn fuel oil, the products of combustion from the furnace 1 passing out 40 the stack 2. 3 is a still of a well-known form placed over said furnace and connected to a water cooled condenser coil 4 by a pipe 5, the liquids from the coil 4 being carried off by the pipe 6.

45 7 is an exhauster, the intake side of which is connected to the pipe 6 near the outlet of the condenser by a pipe 8. The funnel 9 is disposed in the stack 2 and is mounted on the end of a pipe 10 leading into the 50 still 3, the lower end of pipe 10 running close to the bottom of the still and being perforated as shown at 11. The portion of pipe 10 between the cone 9 and still carries a 55 cooler 12, the purpose of which will presently appear. The still 3 is preferably equipped with a thermometer 13. When the

oil in the still has been raised to the desired temperature, the exhauster 7 is set in operation and flue gases from the stack 2 are drawn through the oil in the still and 60 through the condenser by the partial vacuum created by the vacuum pump or exhauster. As the heated gases bubble up through the oil in the still, they give up a part of their heat thus raising the temperature 65 of the oil and reducing the amount of heat to be supplied from the furnace in the usual way. This saving I have found by actual use to be substantial, but the great advantage of passing the furnace gases 70 through the body of oil arises out of the fact that as the heated gases bubble up through the oil they entrain and carry along with them all of the light hydrocarbons and give larger yields of gasolene, kerosene and 75 distillates than can be obtained by any other process known to me. The vapors carried out of the still pass with the furnace gases into the condenser coil 4, where the hydrocarbons are condensed. The gases are drawn 80 off through exhauster 7 while the liquid hydrocarbons flow away through pipe 6. In case the temperature of the flue gases is undesirably high, they may be cooled as 85 much as required by operating the cooler 12. 85

I am aware that it is customary in distilling crude petroleum, when cracking is not desired, to pass steam into the still through a perforated pipe and allow it to bubble through the oil. The steam agitates 90 the oil mechanically and so assists in preventing cracking by maintaining a uniform temperature and it also serves to carry oil vapors off mechanically. However, in steam distillation the fuel consumption is high, the 95 oil received from the condenser has a very poor color and has to be treated with acid and soda in order to get commercial colors, and the yields are low when compared with my process. When using my invention only 100 the last cuts have to be treated in any way to secure commercial color. For example, I have distilled Gulf Coast crude petroleum with my process herein disclosed and have obtained pale lubricating oil direct from 105 the still. This I believe impossible when using steam according to the ordinary methods of distillation.

While I have developed my process primarily for distillation of crude petroleum, 110 it may be applied to the distillation of other hydrocarbons.

Having thus described my invention, I claim:

The method of simultaneously producing pale lubricating oil and distillates including gasolene from crude petroleum oil containing asphalt forming material in material quantities and having high sulfur content as exemplified by Gulf Coast crude petroleum, comprising heating the bottom of a

still containing said crude oil directly by products of combustion, cooling a portion of said products after having used the same under the still, passing said cooled portion through the oil in said still, while heated as aforesaid, and subsequently condensing out the hydrocarbon vapors from said portion.

WILLARD C. AVERILL, JR.
